UNITED STATES PATENT OFFICE.

FREDERICK W. HEDGELAND, OF CHICAGO, ILLINOIS, ASSIGNOR TO THE
W. W. KIMBALL COMPANY, OF SAME PLACE.

QUALIFYING-BOX FOR BASS-REEDS OF ORGANS.

SPECIFICATION forming part of Letters Patent No. 472,998, dated April 19, 1892.

Application filed November 27, 1891. Serial No. 413,319. (No model.)

To all whom it may concern:

Be it known that I, FREDERICK W. HEDGELAND, a citizen of the United States, residing in Chicago, in the county of Cook and State 5 of Illinois, have invented a new and useful Improvement in Qualifying-Boxes for Bass-Reeds, of which the following is a specification.

This invention is intended to improve the tones given out by the reeds employed in the 10 bass of organs; and it consists in the improved construction of the qualifying-box containing the reeds and of the air-passage connecting the same with the bellows.

In the drawings I have shown at Figure 1 a 15 side elevation of an organ-bellows and my improved reed-box for the bass-notes. Fig. 2 is a vertical section of the reed-box.

In the drawings, A represents one of the feeders, B the well, and C the air-reservoir, of 20 any ordinary organ-bellows.

D represents a wind-chest or passage-opening from the well of the bellows and charged with air therefrom. In the bottom of this passage D are located a series of valves e, controlling the admission of air to the cells E of the several reeds. These valves are operated from the pedals F by the pivoted lever f and the pitman f', as will be understood from Fig. 2. The passage or chest D acts as a resonator 25 to the reeds. The cells E are formed in reed board or box G, which is placed in an inclined position, as shown, in order to render the reeds quick in sounding and to avoid the preliminary "buzzing" commonly encountered when 30 the reeds are placed either vertically or horizontally. The air which sounds the reeds (one of which is shown at g) issues into a surrounding box H, which I denominate the "qualifying-box," and which is in effect divided by the reed-board into two chambers 35 h h', one forward of the reed-board and the other in the rear thereof, a connecting-passage h² under the lower edge of the reed-board serving to unite the two chambers. These 40 qualifying-chambers both unite in giving the proper quality to the tone, and they also unite with the resonator-passage D in the performance of this function, so that I may very properly, as I believe, denominate the three as a 45 "triple-qualifying box." If the organist does not wish to sound the bass-reeds contained

in the qualifying-box, they may be prevented from sounding by closing the mute I, located at the rear of chamber h'. He is enabled to do this by raising the rod J, which extends to 55 within reach and is joined to a toggle j, attached to the end of the mute, the shortening of the toggle serving to draw the mute into the closed position. The closing of the mute prevents the passage of any air through the 60 reeds, and thus prevents the letting out of any sound by them.

In front of the passage-box D is a removable board K, by taking away which ready access is had to the reeds for tuning and to 65 the valves for repairs.

I claim—

1. The combination, with an organ, of the bass-reeds, the wind-passage D, acting also as a resonator, and qualifying-chambers h h', 70 communicating with each other, substantially as specified.

2. The combination, with blowing-bellows, of the wind-passage D, the bass-reeds, and qualifying-chambers h h', located one in front 75 of and the other behind the reeds, substantially as set forth.

3. The combination, in an organ, of the bellows, the resonator D, the qualifying-box H, divided by the reed-board into two qualifying-chambers, and the reed-board and reeds, 80 substantially as set forth.

4. The combination, with a wind-supply, of the bass-reeds and a qualifying-box therefor, the reed-board dividing the box into qualifying-chambers, substantially as set forth. 85

5. The combination, with a blowing-bellows and the reeds, of the passage D, charged by the bellows and delivering the air to the reeds and also acting as a resonator to the latter, 90 substantially as set forth.

6. The combination, with an organ, of wind passage or box D, a reed-board, the cells of which open from the bottom of said box, valves for closing said reed-cells, and a front 95 board K, located relative to the valves and reed-board, as shown, and made removable, substantially as set forth.

7. The combination, with blowing-bellows, of wind-passage D, the reeds and their board, 100 the qualifying-chamber h in front of the reeds, the qualifying-chamber h' in rear of the reeds

and communicating with chamber h , and a mute-closing chamber h' , substantially as set forth.

8. The combination, with a blowing-bellows, 5 of the bass-reeds sounded by said bellows, a qualifying-box surrounding and receiving the air passing the reeds, and a mute closing the

air-exit from said box, substantially as set forth.

FREDERICK W. HEDGELAND.
